Inventor:

Edward J. Worcester

United States Patent Office.

EDWARD J. WORCESTER, OF WORCESTER, MASSACHUSETTS, ASSIGNOR
TO HIMSELF AND WILLIAM S. PORTER, OF SAME PLACE.

Letters Patent No. 65,982, dated June 18, 1867.

IMPROVED BRUSH.

The Schedule referred to in these Letters Patent and making part of the same.

KNOW ALL MEN BY THESE PRESENTS:

That I, EDWARD J. WORCESTER, of the city and county of Worcester, and Commonwealth of Massachusetts, have invented certain new and useful improvements in Hand-Brushes; and I do hereby declare that the following is a full, clear, and exact description of the same, reference being had to the accompanying drawings forming a part of this specification, in which—

Figure 1 represents a perspective view of my improved brush.

Figure 2 represents a side view of the handle and metallic connection, upon an enlarged scale; and

Figure 3 represents a cross-section on line A, fig. 1.

To enable those skilled in the art to which my invention belongs to make and use my improved hand-brush, I will proceed to describe it.

In the drawings, B represents the wooden back of the brush, which is made in the usual form, except that both ends are made like the end C, fig. 1; the common mode of making the back being to turn a handle from the stick or piece from which the back is made, the handle projecting from one end of the back. There are objections to this mode of making brushes, since the handle has to project back straight to prevent its splitting off, and consequently the brush cannot be used as conveniently as it could if the handle curved up a little. Again, when the handle is so made the wear comes mostly upon the bristles at the front end D of the brush, and they are soon worn off, and the brush is thrown one side as useless. The foregoing and other objections are all obviated by my present invention, while a thin and light back, B, can be used. E is a thin metal socket-piece, the front under side being so made as to slip over the end of the back B of the brush; its lower edges *a a* clasping the edges of the back B, as fully indicated in the drawings. The end of the back B is forced in until it strikes against the shoulder or end *b* of the recess in the part E. This shoulder is indicated by dotted lines, fig. 2. The end of back B fits the dove-tail recess in the metal connection or socket E so closely that it is held very firm and securely from all lateral motion or play, but to prevent its slipping out, a screw, *c*, is passed through the connection-piece E, as shown in the drawings. The rear end of the metal connection-piece E is provided or made with a ferrule or socket, F, into which the end of handle G is driven.

It will be observed that making the brush in the manner shown and described, the inclination or position of the handle is such as respects the back of the brush that it can be used much more conveniently and effectively than if the handle projected out straight. Again, in case the bristles at the end D become worn off, all that is necessary to do in order to reverse the ends of the back B and bristle part of the brush is to remove screw *c*, and slip off the metal socket or connection-piece E, and slip it on to the end C, and insert the screw *c*, and the brush is again ready for use, with bristle ends D and H reversed.

In making the back B, a screw-hole, *d*, may be made in each end of the back to receive the screw *c*. In making the handle and back separately, as described, a great amount of stock can be saved, since the handles can be turned from waste stock of various kinds. In lieu of a socket or ferrule to receive the handle G, the metal connection or socket-piece E may be made with a shank to be driven into the handle.

Having described my improved hand-brush, what I claim therein as new and of my invention, and desire to secure by Letters Patent, is—

1. The combination of handle G and back B with a removable metal connection-piece or socket, such as described, which can be readily applied to either end of the back of the brush without injuring or defacing the same for the purposes stated.
2. The combination of the back B and handle C with the bent metal socket or connection-piece E, and flanges *a a*, substantially as and for the purposes set forth.

EDWARD J. WORCESTER.
